UNITED STATES PATENT OFFICE.

PERRY A. JONES, OF SEYMORE, INDIANA.

CUFF-HOLDER.

SPECIFICATION forming part of Letters Patent No. 352,757, dated November 16, 1886.

Application filed May 29, 1886. Serial No. 203,577. (No model.)

To all whom it may concern:

Be it known that I, PERRY A. JONES, a citizen of the United States of America, residing at Seymour, in the county of Jackson and State of Indiana, have invented certain new and useful Improvements in a Shirt-Cuff Holder, of which the following is a specification, reference being had therein to the accompanying drawings.

10 My invention relates to improvements in cuff-holders.

The object of my invention is to provide a cuff-holder that may be adjustably attached to shirt-sleeves, or sleeves of other garments, 15 convenient of attachment, efficient in use, and not liable to loose its hold on the sleeve by pressure when secured thereto.

Referring to drawings, Figure 1 is a side view of a shirt sleeve and cuff, having my improved holder attached thereto. Fig. 2 is a perspective view of my cuff-holder. Fig. 3 is a sectional view of a sleeve clasp or tongue and its spring.

S is the sleeve of a shirt; C, the cuff.

25 A, B are parallel or nearly parallel bars, which may be made square, round, or flat. To one end of bars A, B is attached the stud or post c, to which the button b is trunnioned near its upper ends by means of lugs H, H, set eccentrically on its inward face.

F is a spring securely fastened to the inward face of button b near its outward rim, then passing across its disk to a point between lugs H, H, where its free end rests on post c.

35 At the other ends of the bars A, B are cross-bars or an L-shaped lateral projection forming jaws, c', c', in which the tongue or clasp B' is trunnioned at I to be operated on by spring B². The spring B² is firmly secured to jaws c', c' by stirrup G, and forms a floor between the jaws, providing a smooth bearing-surface 40 resting on the arm. At the trunnioned end of clasp or tongue B', Fig. 3, is seen a V-shaped notch, E, into which the free end of the spring B' drops when the clasp is opened, as seen in Fig. 2. Pressing on the clasp returns it to its position between the jaws, where it is firmly held by the spring, as seen in sectional view, Fig. 3. By turning the button b in a perpen-

50 dicular position with reference to the bars A, B, as seen in Fig. 2, it is then inserted in the

holes of the cuff; then by a slight pressure of the thumb the button is pressed back to its horizontal position, securely retaining the cuff, the spring F on the button, when in this position, resting at its free end on top of post c, holding the button firmly in place. The cuff-holder, by means of its clasp B' and jaws c', c', is adjustably secured to the sleeve S. This adjustment regulates the position of the cuff 60 on the wrist. The firm hold taken on the shirt-sleeve by the clasp is very much increased by the roughened under surface of the same, and also by the intervening edges of the clasp and jaws, over which the fabric is drawn by the 65 constant pressure of the clasp maintained by the spring.

It will be noticed that it is impossible to release the hold of the clasp on the sleeve by the arm resting on the desk or table, as is the case 70 with some cuff-holders. On the contrary, such pressure tends to increase its hold.

Having thus described my invention, what I claim, and desire to secure by Letters Patent, is—

75 1. A cuff-holder consisting of the parallel bars A, B, jaws C, C', secured to said bars, the pivoted clasp B', the spring B², and a button for connection with the cuff, substantially as set forth.

80 2. The cuff-button b, having lugs H, H secured to one side of center, or eccentrically on under side of said button, in combination with post c, parallel bars A, B, spring F, and a clasp for securing the device to the sleeve, as 85 set forth.

3. A cuff-holder having at one end means, substantially as described, for connecting with a cuff, and provided at its other end with lateral jaws C', combined with a clasp, B', and 90 spring B², all being constructed and arranged substantially as set forth.

4. The combination, in a cuff-holder provided at one end with means, substantially as described, for connecting with a cuff, of jaws 95 C', arranged at the opposite end of such holder, the clasp B', the spring B², and the stirrup G, as and for the purposes specified.

PERRY A. JONES.
